UNITED STATES PATENT OFFICE.

KUWAKICHI FUJITA AND GEORGE BUSHAR MARKLE, JR., OF HAZLETON, PENNSYLVANIA.

ROTARY ENGINE.

1,187,298.

Specification of Letters Patent. Patented June 13, 1916.

Application filed November 15, 1915. Serial No. 61,606.

To all whom it may concern:

Be it known that we, KUWAKICHI FUJITA, a subject of the Mikado of Japan, and GEORGE B. MARKLE, Jr., a citizen of the 5 United States, both residents of Hazleton, in the county of Luzerne and State of Pennsylvania, have invented a new and Improved Rotary Engine, of which the following is a full, clear, and exact description.

Our invention relates to an internal combustion engine of the rotary type.

The object of the invention is to provide a simple and efficient rotary engine the 15 stator and rotor of which form a combustion chamber and turbine elements at the ends of said chamber to be actuated by combustion gases of the chamber.

With the above and other objects in view, 20 the nature of which will more fully appear as the description proceeds, the invention consists in the novel construction, combination and arrangement of parts as herein fully described, illustrated and claimed.

25 In the accompanying drawings, forming part of the application, similar characters of reference indicate corresponding parts in all the views.

Figure 1 is a longitudinal section through 30 our rotary engine; Fig. 2 is a cross section on line 2—2, Fig. 1; Fig. 3 is a similar section on line 3—3, Fig. 1; Fig. 4 is a cross section on line 4—4, Fig. 1; Fig. 5 is a similar section on line 5—5, Fig. 1; and 35 Fig. 6 is a fragmentary perspective view of the lining of one of the turbine chambers.

Referring to the drawings, 7 is a stator, 40 preferably formed of two semi-cylindrical, double-walled sections adapted to be secured to each other by any suitable means. The inner periphery of the stator has an annular recess 8 in the central part thereof. A lining member 9 engages the recess 8, 45 and means are provided for preventing the rotation of the lining relative to the stator. The inner periphery of the lining has an annular recess 9' extending substantially

through the length of the lining. Cups 10 are provided on the periphery of the recess 50 to present a large heating surface.

A lining ring 11 is provided within the stator at each end of the lining 9. The inner, lateral surface of the ring is depressed eccentrically at uniform intervals 55 whereby eccentric pockets 12 are formed on the inner periphery of the ring, each pocket having one end wall forming the abutting or reacting end of the pocket (see Fig. 3). The end walls of the lining 9 have 60 spirally-shaped grooves 22, each terminating in a port 23. These spiral grooves establish communication between the recess 9' of the lining 9 with the eccentric pockets 12 of the lining 11, for each port 23 is at 65 the reacting end of a corresponding pocket. It will be noted that the depth of the reacting end increases as the pocket approaches the outlet 13 in the ring which leads to a similar ring 14, preferably of 70 the same diameter but wider than the ring 11, and spaced from the ring 11 by a double-walled, annular partition 15. A similar partition 16 spaces the ring 14 in the stator from a ring 17, also similar to ring 11 but 75 slightly wider than the ring 14. The end wall 18 of the stator is double-walled and preferably extends inwardly to align with the partitions 15 and 16.

It will be noted from Fig. 4 that the outlet 80 13 from the ring 11 enters the reacting end of the eccentric pocket 19 of the ring 14 which has the least depth. The outlet 20 from said ring, which is formed in the deepest pocket 19 of the ring at the shallow 85 end thereof, enters the reacting end of the eccentric pocket 21 of the ring 17 which has the least depth. The rings and stator have means whereby the rotation of the rings within the stator is prevented.

90 A tubular rotor 24 is provided with annular grooves 25 and 26 on the outer periphery thereof for engaging the partitions 15 and 16 respectively. The outer periphery of the rotor 24 is also reduced at the 95 ends to fit the end walls 18. The bottom

of the grooves 25 and 26, and the reduced portion at the end, are grooved to receive packing rings. The outer periphery of the rotor opposite the lining is reduced uniformly to the inner diameter of the lining of the end walls. The reduced portion of the rotor facing the cups 10 is provided with buckets 27. Annular rotor portions 28, 29 and 30, circumscribed by the rings 17, 10 14 and 11 respectively, form, with the corresponding rings a turbine element. The periphery of each of the rotor portions 28, 29 and 30 is toothed, and the depth of the teeth increases with the increase of width 15 of the rotor portion, to compensate for the necessary expansion of the gases as they pass from one turbine element to the next turbine element. The teeth 31 of the buckets of the rotor portions are inclined 20 toward the abutting ends of the eccentric pockets in the corresponding rings.

The annular space formed by the lining 9 with the rotor 24 is the combustion chamber of the engine. A fuel discharge 32 is located in a suitable part of the chamber. 25 Although one discharge only is shown in the drawings, more than one can be provided if desired. The discharge is adapted to spray the fuel within the annular space on 30 to the cups. The part of the liquid which does not fall directly upon the cups 10 will fall on the rotor, from which the liquid will be thrown on to the cups. The fuel discharge 32 leads to a casing 33 of a rotary 35 valve 34. A fuel supply 35 from a pump or gravity feed is connected to the end wall of the valve casing 33. A return conduit 36 is also connected to the valve casing 33 diametrically opposite to the conduit from the 40 casing to the discharge 32. The rotary valve 34 is open at the end so that the fuel from the inlet 35 is free to enter the valve. The valve 34 has a port at 37 which is adapted to alternately register with the return conduit 36 or the conduit leading to the discharge 32. Therefore when the discharge 32 is cut off by the valve 34 the oil coming from the inlet conduit 35 is returned 45 through the conduit 36. The valve casing 33 has at the opposite end thereof a compressed air supply 38. The casing has also on the lateral surface diametrically opposite openings 39 and 40. The opening 39 leads to the combustion 50 chamber of the engine, while the opening 40 is connected by conduits to the turbine elements directly in communication with the combustion chamber. Automatic check valves 55 of known type are provided on the 55 conduits from the rotary valve to the stator 7. The rotary valve 34 has a port 41 adapted to register successively with the openings 39 and 40 in the casing. The relation 60 between the ports 41 and 37 in the rotary

valve 34 is such that when the valve admits 65 fuel into the combustion chamber, air is admitted to the turbine elements; and when air is admitted to the combustion chamber, fuel thereto is cut off. Fuel and air are supplied to the combustion chamber and turbine 70 elements under pressure. The rotary valve 34 and the casing 33 are slightly cone shape on their fitting surfaces, and a spring 42 provided within the casing automatically takes up any wear between the valve and 75 casing.

The valve 34 is secured to a shaft 43 which is driven from the main shaft 44 keyed to the hub 45 of the rotor 24. The hub 45 is connected to the inner periphery of the rotor by vanes 46 which, when the rotor is revolved, cause a suction through the rotor. The shaft 44 bears in supports 47 and 48 which have extensions 49 for engaging the stator 7, this extension forming the base of 85 the engine. The end support 48 is preferably closed and provided with a tube 50 which forms an outlet for the air drawn by the vanes through the rotor. To accelerate the cooling of the rotor, in addition to the 90 air drawn therethrough, a cooling liquid is sprayed therewith through a perforated conduit 51. The stator is cooled by circulating water between the walls of the stator. The fuel discharged into the annular combustion chamber of the engine, mixed with the air forced thereinto, is ignited by a 95 spark plug 52, the sparks of which are generated by a magnet 53 driven from the valve shaft 43.

To start the engine, a certain amount of fuel and air is admitted into the combustion chamber and the same ignited by causing a spark within. The explosion or combustion of the fuel within the combustion chamber 105 will drive the gases of combustion from the combustion chamber through the spirally-shaped grooves into the adjacent turbine elements, acting on the teeth of the rotary portion 30 and the abutting or reacting end of 110 the pocket thereby setting the rotor in movement. The gases of combustion from the first turbine element enter the second turbine element through the outlet 13, acting on the teeth of the rotor portion 29 and the 115 reacting ends of the pockets, thereby also adding to the rotary movement of the rotor. From the second turbine element the gases will pass into the third turbine element and act on the teeth of the rotary portion 28, 120 from where the gases exhaust through an exhaust opening 54. The rotor being set into motion will operate the rotary valve 34 and thereby fuel will be injected into the combustion chamber. The combustion chamber, being hot from previous explosions of the mixture, will vaporize the liquid fuel 125 falling upon the cups. The subsequent ad-

mission of air by the valve will mix the gases with the air and the same will be ignited by the magneto, properly timed, the combustion gases again passing from the chamber into the adjacent turbine elements.

It will be noted that during the admission of fuel into the combustion chamber, air is admitted to the turbine elements in communication with the combustion chamber. This 10 admission of air under pressure to the turbine elements at the end of the combustion chamber causes the compression of the fuel gas in the chamber. It helps to scavenge the turbine elements and also prevents the 15 fuel gases from escaping before being ignited. The air coming from the turbine elements into the combustion chamber helps to make a more perfect mixture of the fuel gases within the combustion chamber. The 20 successive concentric pockets within the turbine elements, which increase in depth as the pockets approach the outlet from the turbine element compensate for the expansion of the combustion gases as they 25 approach the outlet.

We claim:

1. In a rotary engine, a stator, a rotor, said rotor and stator forming a combustion chamber between the ends thereof and turbine elements at the ends in communication with the ends of the chamber, fuel-supplying means for the combustion chamber, air-supplying means for the combustion chamber and turbine elements, means for admitting successively fuel and air into the combustion chamber, said means adapted to supply air to the turbine elements while the supply of air to the combustion chamber is cut off, and means for igniting the fuel within the combustion chamber.

2. In a rotary engine, a rotor, a stator, said stator and rotor forming an annular combustion chamber, said stator and rotor also forming turbine elements, each end of 45 said combustion chamber having outlets to the adjacent turbine elements, air-supplying means to the combustion chamber and the adjacent turbine elements, fuel-supplying means for the combustion chamber, the 50 lateral surface of said chamber being irregular to present a maximum surface, means controlling the supply of air and fuel to the chamber and turbine elements so that fuel and air is successively admitted to the combustion chamber and air is admitted to the 55 turbine elements when fuel is supplied to the chamber, and means for igniting the fuel in the chamber.

3. In a rotary engine, a stator, a rotor 60 within the stator forming therewith an annular combustion chamber, said stator having cups within the combustion chamber on the lateral surface of the stator, said rotor having buckets within the combustion chamber.

ber on the lateral surface of the rotor, fuel-supplying means, fuel discharges within the combustion chamber associated with the fuel-supplying means, air-supplying means, a valve associated with the fuel- and air-supplying means and adapted to successively 65 admit air and fuel to the combustion chamber, means for igniting the fuel within the chamber, said stator and rotor forming successive turbine elements at each end of the combustion chamber, the adjacent turbine 70 elements being in communication, said chamber communicating with the adjacent turbine elements, said valve adapted to supply air to said turbine elements adjacent the chamber when the air from the chamber is 75 cut off by said valve.

4. In a rotary engine, a stator, a rotor, said stator and rotor forming a combustion chamber, said stator and rotor forming also turbine elements in communication with the 85 combustion chamber, fuel-supplying means for said chamber, air-supplying means for said chamber and turbine elements, and controlling means for said fuel and air supply whereby air and fuel are successively admitted to the chamber and air admitted to the turbine element when it is cut off from the chamber, said stator having eccentric pockets in the turbine elements, each pocket presenting a single reacting end, the depth 90 of said pockets increasing as said pockets approach the outlet from the turbine element, said rotor having teeth within the turbine element coöperating with the reacting ends of the pockets thereof.

5. In a rotary engine, a stator having a plurality of annular partitions adjacent the ends thereof, a rotor having annular grooves engaging the partitions of the stator, said stator and rotor forming a combustion chamber between the pluralities of partitions, teeth on the periphery of the rotor portions located between the partitions, said stator having eccentric pockets between said partitions, each of said pockets presenting a 105 single reacting end, said partitions having openings establishing communication between the adjacent annular spaces formed by said partitions, said partitions having openings therethrough for establishing communication between the adjacent annular compartments formed by the partition engaging the grooves of the rotor, means for supplying a fuel mixture in the combustion chamber, and means for igniting the mixture.

6. In a rotary engine, a stator, a rotor forming with the stator a combustion chamber between the ends thereof and turbine elements at the ends in communication with the ends of the chamber, fuel supply means 115 for the combustion chamber, means for supplying air to the chamber directly and through the communication between the

chamber and the turbine elements, means for controlling the admission of air and fuel adapted to simultaneously supply fuel and air through the communication between the 5 chamber and the turbine elements whereby the fuel is prevented from escaping from the chamber and the turbine elements, said controlling means supplying air directly to the chamber when the fuel supply thereto is cut 10 off, and ignition means within the chamber

for igniting the fuel mixture subsequent to the direct admission of air.

In testimony whereof we have signed our names to this specification in the presence of two subscribing witnesses.

KUWAKICHI FUJITA.
